(No Model.)

F. W. MINSHALL.

PROCESS OF AND APPARATUS FOR DISTILLING AND DESULPHURIZING
HYDROCARBON OIL.

No. 415,876.

Patented Nov. 26, 1889.

UNITED STATES PATENT OFFICE.

FRANK W. MINSHALL, OF MARIETTA, OHIO.

PROCESS OF AND APPARATUS FOR DISTILLING AND DESULPHURIZING HYDROCARBON OIL.

SPECIFICATION forming part of Letters Patent No. 415,876, dated November 26, 1889.

Application filed August 8, 1889. Serial No. 320,091. (No model.)

To all whom it may concern:

Be it known that I, FRANK W. MINSHALL, a citizen of the United States, residing at Marietta, in the county of Washington and State 5 of Ohio, have invented a new and useful Improvement in the Process of and Apparatus for Distilling and Desulphurizing Hydrocarbon Oil, of which the following is a specification.

10 My invention relates to an improvement whereby the heavier or crude hydrocarbon oils may by a continuous or uninterrupted process be distilled and at the same time relieved of sulphur to render the distillate de- 15 void of any sulphurous constituent; and I accomplish the object of my invention, broadly stated, by injecting hydrocarbon oil to be distilled and desulphurized with super-heated steam and oxygen into a retort and 20 automatically maintaining a constant or substantially constant temperature inside the retort.

The apparatus for the practice of my improved process is illustrated in Figure 1 of 25 the accompanying drawings in elevation, partly broken, and sectional; and Fig. 2 shows by an enlarged view in sectional elevation the pressure-regulating valve used with the apparatus.

30 A is an ordinary cylinder still or retort, supported over a suitable furnace B, having a fire-chamber r and the common appurtenances thereto, and C is the condenser, communicating through a conduit q with the retort near the rear end of the latter, and also 35 communicating therewith through a pipe q', extending into the retort near its base. The pipes q and q' serve, respectively, to conduct the vapors and residuum (tar) of distillation 40 into the condenser, all in a usual manner, the parts thus far described corresponding with those in common use for distilling hydrocarbon oils.

Inside and lengthwise of the retort A, near 45 its base, is a thermostat D, comprising a brass rod p, preferably about three-fourths of an inch in diameter, inside an extra-heavy iron pipe p', of a diameter to admit the rod p without binding, and supported at one end in the 50 forward head of the retort-cylinder and adjacent wall and toward its opposite end, which is closed with a plug p², having a central

threaded socket, as shown, by a suitable leg p³. The rod p is screwed at one end into the socket of the plug p², and extends thence 55 through the pipe p' and through a stuffing-box p', provided in its outer end, and in which the brass rod works freely when expanded or contracted by the temperature within the retort beyond the forward end of the retort- 60 cylinder.

E is a steam-boiler adjacent to the retort, and between the two is a small steam-chest F, suitably and firmly supported, as indicated, and having in its upper side ports x and x', 65 into which lead, respectively, a pipe o, communicating through a branch pipe o' with the steam-dome of the boiler, and a pipe n, communicating at its end, controllably, with the outer air, and between its extremities, through 70 a pipe n', with one end of a superheater-coil G in the fire-chamber r, the opposite end of the coil G leading into the pipe o. In the steam-chest F is a piston-valve F', actuated from a valve-rod m, extending through an 75 end of the steam-chest and through a suitable stuffing-box m', and pivotally connected with an end of a lever H, fulcrumed between its extremities, as shown at y, and pivoted at its opposite end to the projecting end of the 80 thermostat-rod p.

On the under side of the steam-chest F are ports x² and x³, coinciding, respectively, with the ports x and x', and with both of which communicates a pipe l through two branches l' 85 and l². The pipe l leads from the aforesaid branches into a box or chamber k, opening at one end into the retort A, and communicating from its opposite end through a pipe i, having a valve i', with the oil-supply reservoir I, near the base of the latter, and from which an overflow-pipe i' leads to a suitable receptacle I'. A branch pipe h, provided with a valve h', leads from the pipe l into a box or chamber k', like the box k, opening 90 into the retort-cylinder, and communicating at its outer end through a pipe g, provided with a valve g', with the outer air or other supply of oxygen, and a thermometer K, the measuring capacity of which should reach as 100 high as 650° Fahrenheit, is provided in the pipe h. In the pipe l, I provide a pressure-regulating valve L and in the conduit q an ordinary spring check-valve e, and the pipes

o, o', n, l, and q should be provided with suitable valves, as indicated, to control the passages through them.

To practice my improved process I first introduce into the retort A a quantity of hydrocarbon oil of so heavy a quality that it will require a temperature above 500° Fahrenheit to boil it, the quantity introduced being sufficient to cover the pipe *p'* of the thermostat D. Fire is then started in the chamber *r* and the oil in the retort heated to 500° Fahrenheit, and steam is introduced from the boiler E into the superheater-coil G by closing the valve *f* in the pipe *o* and opening the valve *f'* therein. The valve in the pipe *o'* and the valve *f* in the pipe *n* are left open to allow the superheating steam to blow off until its temperature reaches 500° Fahrenheit, when the blow-off is closed and the valve *f* in the pipe *n* opened to permit the superheated steam to enter the chest F through the port *x'*, and thence by way of the pipe *l* from the port *x* into the retort through the box *k*. The spring of the check-valve *d* in the conduit *q* is so adjusted as to make sufficient back-pressure to maintain the retort A filled with the superheated steam. With the introduction of superheated steam into the retort A the valve *i'* in the oil-supply pipe *i* and the valve *g*, controlling communication of the box *k'* with the open air, (or with another supply of oxygen,) are opened, the fire in the chamber *r* being continued to generate the heat required. Thus the hydrocarbon oil to be treated is subjected continuously to a temperature maintained constantly at about 500° Fahrenheit by the automatic action of the thermostat, which is as follows: The initial adjustment of the valve F' in the steam-chest F is such that when the temperature inside the retort is 500° Fahrenheit the valve F' is in the position illustrated, wherein it closes the port *x* for common steam and opens the port *x'* for superheated steam. With an increase in the temperature expansion of the rod *p* actuates the lever *II* to close partially or completely, as required, the superheated-steam inlet and open that for common steam from the boiler E, whereby entrance of such common or wet steam into the retort is permitted and produces lowering of the temperature, which, when it becomes reduced below that stated, actuates the valve F' by contraction of the rod *p* to admit more superheated steam and less or no steam from the boiler.

The oil placed in the retort A, which should be of greater specific gravity than that in the receptacle I, aids in maintaining constant the temperature inside the retort, since, because it boils at a certain temperature (as 500° Fahrenheit) and is continuously supplied with heat from the furnace and with superheated steam at a higher temperature, inasmuch as it cannot, so long as it is free to evaporate, be raised to a temperature beyond

the boiling-point, it will, when boiling, take readily the extra heat from the furnace and superheated steam, and the rod *p*, immersed in it, will in turn absorb it from the liquid, which thus conveys it to the rod, causing the latter by its consequent expansion to control the valve F' to reduce the temperature of the steam.

While 500° Fahrenheit is mentioned as the desired normal temperature to be maintained in the retort, it may be increased or diminished in accordance with particular requirement and by proper adjustment of the valve F' in its steam-chest F.

The hydrocarbon oil supplied to the receptacle I is introduced into the retort with a jet of steam, which effects the introduction in a thoroughly-atomized condition of the oil, and at the same time the oxygen introduced by the steam-jet through the pipe *g* and box *k'* is brought into intimate contact with the sulphur contained in the oil at a temperature favorable to chemical union therewith.

The presence of a body of steam in the retort prevents therein any sudden increase of temperature as might otherwise be produced by the chemical union of the sulphur and oxygen.

All that portion of the injected hydrocarbon oil which boils at and below 500° Fahrenheit is converted by the action described into vapor, which passes off through the conduit *q* into the condenser. The residuum of distillation (a tar-like substance) accumulates at the bottom of the retort, whence it may be drawn off from time to time through the pipe *q*, and the sulphurous-oxide gas passes into the condenser with the distillate, from which it may be readily separated in any suitable or well-known manner.

The purpose of the pressure-regulating valve L is to produce uniform pressure in the boxes *k* and *k'*, and the provision of an overflow from the supply-receptacle I induces unvarying pressure on the valve *i'* in the supply-pipe *i*, the arrangement insuring the delivery into the retort of steam, hydrocarbon oil, and oxygen or other agent in unvarying quantities proportional according to requirement.

What I claim as new, and desire to secure by Letters Patent, is—

1. The process of distilling and desulphurizing volatile hydrocarbon oils, which consists in heating a quantity of hydrocarbon oil of high specific gravity in a still, and injecting a lighter hydrocarbon oil into the still with steam and oxygen, the steam being alternately superheated or wet, according to the temperature of the bath, substantially as and for the purpose described.

2. In an apparatus for distilling and desulphurizing hydrocarbon oil, the combination of a retort A, a suitable fire-chamber, a superheater G, communicating with a steam-generator, a thermostat D in the retort, a steam-chest F, communicating with the steam-generator.

ator and superheater and with the retort A, a valve F' in the steam-chest and connected with and controlled by the thermostat, and an oil-supply pipe and an oxygen-supply pipe, 5 both leading into the retort with the steam-supply, substantially as described.

3. In an apparatus for distilling and desulphurizing hydrocarbon oil, the combination of a retort A, having chambers k and k' leading into it, and communicating, respectively, with the oil-supply pipe and the supply-pipe of oxygen, a fire-chamber r, containing a superheater G, communicating with a steam-generator, a thermostat D in the retort, a 10 steam-chest F, communicating from one side with the steam-generator and superheater and from its opposite side with the retort at the chambers k and k', and a valve F' in the steam-chest connected with and controlled by 15 the thermostat, substantially as described.

4. In an apparatus for distilling and desulphurizing hydrocarbon oil, the combination of a retort A, having chambers k and k' leading into it, and communicating, respectively, with 20 the oil-supply pipe and the supply-pipe of oxygen, a fire-chamber r, containing a superheater G, communicating with a steam-generator E, a thermostat D, comprising a metal rod p within a tube p', supported in the 25 retort, a steam-chest F, communicating from one side with the steam-generator and superheater and from its opposite side with the retort at the chambers k and k', a pressure-

regulator L in the communication of the steam-chest with the retort, a piston-valve F' 35 in the steam-chest F, and a lever H, connecting the piston-valve with the rod p, substantially as described.

5. In an apparatus for distilling and desulphurizing hydrocarbon oil, the combination, 40 with a condenser C, boiler E, and oil-receptacle I, of a retort A, having chambers k and k' leading into it, and communicating, respectively, with the receptacle I and the supply-pipe of oxygen, a fire-chamber r, containing 45 a superheater G, communicating with the boiler E, a thermostat D in the retort, a steam-chest F, having ports x and x' in one side and ports x² and x³ in its opposite side, and communicating at the ports x and x', respectively, with the boiler and superheater, a valve F' in the steam-chest, connected with and controlled by the thermostat, a pipe l, communicating at one end with the steam-chest at the ports x² and x³, and leading into the 55 chamber k, a pressure-regulator L in the pipe l, a branch pipe h, leading from the pipe l into the chamber k', an overflow for the receptacle I, and a tar-pipe q, leading from the retort, the whole being constructed and arranged to 60 operate substantially as described.

FRANK W. MINSHALL.
